UNITED STATES PATENT OFFICE.

JOHANN J. R. HAALCK, OF BAKERSFIELD, CALIFORNIA.

BOAT-TRANSPORTING APPARATUS.

Application filed March 25, 1924. Serial No. 701,724.

To all whom it may concern:

Be it known that I, JOHANN JURGEN RICHARD HAALCK, a citizen of Germany, (who has declared his intention to become 5 a citizen of the United States), residing at Bakersfield, in the county of Kern and State of California, have invented certain new and useful Improvements in Boat-Transporting Apparatus, of which the following is a 10 specification, reference being had to the accompanying drawings.

This invention relates to means for transporting boats of the general character of the apparatus illustrated in my previous 15 Patents #1,259,620, of March 19, 1918, #1,259,619, of March 19, 1918, and #1,283-744, of November 5, 1918. These patents all disclose a boat transporting structure whereby a boat may be carried from one 20 body of water to another at a different altitude so as to thus permit the boat to be transported across hills divides and up and down hillsides from a lower to a higher point and vice versa while the boat is held 25 in a horizontal position at all times, the mechanism being particularly designed to be used in connection with a series of canals at different levels.

More specifically, my present object is to 30 provide a structure operating on an inclined rail bed and moving into the water of a relatively low river or canal at the base of said rail bed, movable over the rails to a higher level and into the water of a second 35 canal or waterway at a higher level, this structure including a wheeled transporting structure adapted to be shifted into position beneath the boat in relatively deep water and then shifted with the boat into 40 relatively shallower water so that the bed for the boat which is carried by the transporting structure will gradually rise beneath the bottom of the boat and lift it up until the boat rests entirely upon the bed, and to 45 provide means whereby either end of the boat may be raised to thus cause the boat to stay on an even keel while the transporter is moving upon the inclined track, means being provided, of course, whereby 50 the raised end of the rail bed may be lowered again as the transporter nears a hori-

zontal portion of the track or a portion of the track which is at a less inclination so as to thereby keep the boat on an even keel.

A further object is to provide a structure 55 of this kind which is so arranged that vessels of different lengths may be readily accommodated and transported without any change in the structure.

A still further object is to provide a 60 cradle or bed for the vessel of such character that no injury will be done to the vessel and that the vessel will be yieldingly supported.

Another object is to provide improved 65 means whereby the boat may be tilted with relation to the main structure of the transporter and whereby the driving mechanism of the transporter and the means for tilting may be entirely controlled by a single operator 70 and by very simple mechanism.

Still another object is to provide means for locking the bed structure or cradle at one end to the main frame of the transporter so as to prevent this end from leaving 75 the bearings in which it is supported, while the other end is left free to be raised or lowered by the elevating mechanism.

Other objects will appear in the course 80 of the following description.

My invention is illustrated in the accompanying drawings, wherein:—

Figure 1 is a cross sectional view through a canal or other body of water showing my boat transporting apparatus in end elevation;

Figure 2 is a side elevation of the boat transporting apparatus showing the position taken by the parts when the transporter is moving up an incline;

Figure 3 is a like view to Figure 1 but showing the transporter on level ground, the side wall of the house being broken away;

Figure 4 is a fragmentary top plan view 95 of the bed on which the boat is supported;

Figure 5 is a top plan view of the mechanism whereby the lifting screws are operated;

Figure 6 is a top plan view of the mechanism 100 whereby the transporter is caused to travel backward and forward;

Figure 7 is a fragmentary perspective view of the transporter frame and the elevating frame, showing the jack screws;

Figure 8 is a fragmentary vertical sectional view through the transporter and the elevator, showing the jack screws and the means for operating the same;

Figure 9 is a fragmentary side elevation of the main frame of the conveyor and the elevating frame, showing the bolt for locking the elevator frame to its trunnions and showing the manner of operating the boat;

Figure 10 is a perspective view showing the transporter and the elevator and the pivotal support for the latter;

Figure 11 is a perspective view showing the manner in which the trunnions are supported upon the transporter frame;

Figure 12 is a horizontal sectional view through the transporter frame and the elevator frame, showing the manner of operating the locking bolt 44.

Referring to these drawings, it will be seen that the main frame of the transporter, which main frame is generally designated 10, has a length about that of the average vessel to be handled and a width greater than the average vessel to be handled. While I have illustrated this main frame and its transporter as consisting of longitudinal members 11 and vertical members 12 with cross braces or stays 13, I do not wish to be limited to this as it might be constructed in any suitable manner and the beams 11 and 12 may be made of angle iron, channel iron or of wood, if necessary, and any other means of bracing the frame and rendering it rigid may be used. This frame is open-ended and the frame is operatively supported at each end upon trucks 14 having axles 15 carrying wheels 16, these wheels running upon rails 17. The rails 17 constitute the track and for a portion of the length of the track extend horizontally beneath the water of a pool or basin and then extend upward at an inclination to the height to be reached and then may extend again horizontally and into a pool or basin at this relatively higher altitude or may extend downward to another basin at the same altitude as the first basin.

In the one case the vessel is to be transported up a hillside into the upper basin and in the other case the vessel is to be transported over a hill or divide and carried down into water which is approximately on a level with that of the first basin or pool. It will be understood that these basins or pools referred to are merely enlargements of a canal or other waterway.

This main frame carries upon it the house 18 wherein the mechanism for driving the main frame is located and wherein the electric motor is located. The electric motor is operatively connected to the wheels 16

so as to drive the same, and I have illustrated for this purpose one of the axles 15 at each end of the machine (or both axles if desired) as having mounted thereon a beveled gear wheel 19, this beveled gear wheel being driven by a beveled gear wheel 20 mounted upon a vertical shaft 21 and extending into the house 18 and being operatively connected to the driving mechanism as will appear more fully hereinafter.

Inasmuch as the wheels 16 running upon the tracks 17 would have but a relatively small tractive effect where the transporter is moving up an incline, I preferably provide rails 22 also mounted upon the cross ties 23 of the track structure, these rails 22 being cogged or toothed, and there being mounted upon the shafts or axles 15 gear wheels 24 which mesh with these cogged rails 22. Any other means for mechanically forcing the structure to move along the rails might be used.

The main frame is provided at opposite ends with the brackets 25 having laterally projecting trunnions 26, and disposed within the main frame is the vessel elevating frame, designated generally 27, and illustrated as consisting of the longitudinal members 28 and 29, the vertical members 30, and bracing struts or truss rods 31. I do not wish to be limited to any particular construction for this lifting frame, as it might be constructed in various ways without departing from the spirit of the invention. As illustrated, the lower beams 28 are longer than the main frame 10 and project beyond the ends of this main frame at 28a. Adjacent the opposite ends of each of the members 28 there is provided the bearings 32 which are adapted to rest upon the trunnions 26. When the elevating frame or lifting frame 27 is disposed in a horizontal position, both of these bearings 32 rest upon the trunnions 26. When, however, one end of the lifting frame is raised the bearing members at that end lift off of the corresponding trunnions 26, while the bearing members at the opposite ends rest upon the trunnions. These trunnions, therefore, constitute the fulcrums for the elevating frame. This elevating frame at one side is provided with a plurality of upwardly extending posts 33, to which the vessel A is adapted to be tied. The opposite ends of the vessel elevating frame are adapted to be raised by means of the jack screws 34. I have shown four of these jack screws mounted in bearings in the end members 35 of the main frame, and each set of these jack screws pass through and have screw-threaded engagement with a transverse beam 36. This transverse beam 36 is adapted to engage beneath the projecting ends 28a of the beams 28 when the beam 36 is raised. These jack screws are rotatable

110
115
120
125
130

at their upper ends in the beam 35 and at their lower ends in the transverse beam 37 forming part of the main frame, and each jack screw at its lower end carries a beveled gear wheel 38 engaging the beveled gear wheel 39 mounted upon a transverse shaft 40, which in turn is operated from the driving mechanism, as will be later described. It is obvious now that if the jack 10 screws 34 at one end of the main frame are operated, that end of the vessel elevating frame will be lifted. The means whereby this lifting operation is secured will be hereafter described.

15 Connected to the longitudinal members 29 at intervals are coiled contractile springs 41, these springs being connected to a series of links 42, to which transversely extending cables 43 are connected, the cables and the 20 springs together constituting a bed or cradle which will conform more or less to the shape of the hull of the boat and will yieldingly support the same and so support the boat that the strain will be distributed over the 25 entire structure to a considerable extent. It will be understood that a boat smaller than the supporting frame or longer than the supporting frame may be lifted if desired, and that while the transporter will be of a 30 length adapted to certain types of vessels or boats, variations in length and width are provided for.

The longitudinal beams 28 extend beyond the end supports 30 of the elevating frame 35 27, there being a plurality of these longitudinal beams 28, as shown in Figure 1, and this is for the purpose of permitting that end of the elevating frame which is to turn upon the trunnions 26 to be locked from 40 movement away from these trunnions, while the other end of this elevating frame may be unlocked. To this end, each end of the elevating frame is provided with a transversely extending locking bar 44 mounted in guides in the end vertical members 12, this locking bar 44 being provided with rack teeth 45. There are two of these bars located at opposite ends of the machine and operated by means of gear wheels 46 carried upon the ends of the manually operable shafts 47 which extend into the operating house 18. By rotating this shaft 47 in one direction the locking bar will be projected and in the opposite direction the locking bar will be withdrawn. Thus it will be seen that the elevating frame may be locked down to one of the pairs of trunnions, while the opposite end of the elevating frame is unlocked so as to permit it to be raised and lowered. This locking device prevents the elevating frame under any circumstances from escaping from its trunnions.

60 The driving and elevating mechanism has before been referred to. The means whereby the shaft 21 is driven and whereby the ele-

vating screws are operated is as follows: The shaft 21 has at its end opposite the gear wheel 20 the beveled gear wheel 48 which meshes with a beveled gear wheel 49 on a shaft 50. Mounted on the same shaft is a 70 beveled gear wheel 51 which engages a beveled gear wheel 52 on shaft 21 having gear wheel 20 which engages the beveled gear wheel 19 on a like shaft 15 at the opposite end of the machine. The shaft 50 carries at 75 one end the sprocket wheel 53, and also has mounted upon it the toothed gear wheel 54. A power driven shaft 55 is driven from the motor by means of a belt 56 or any other suitable means, the belt passing over a pulley 57, and this shaft is preferably formed in two parts, there being a friction clutch or friction block 58 between the two sections 55 and 55^a so that there will be a slight yield sufficient to prevent too great a shock coming 80 upon the driving mechanism when the load is first lifted.

85 Mounted upon this shaft 55 is the sprocket wheel 59 and gear wheel 60, the gear wheel 60 meshing with the gear wheel 54, while over the sprocket wheels 59 and 53 passes the sprocket chain 61. The sprocket wheel 59 and the gear wheel 60 are loose upon the shaft 55, but splined upon this shaft is a shiftable clutch 62 operated by means of a lever 63, and when this clutch is thrown into engagement with the sprocket wheel 59, this sprocket wheel is caused to turn while the gear wheel 60 remains idle, and then the clutch is shifted in the opposite direction, the gear wheel 60 turns, and the sprocket wheel remains idle. Thus it will be seen that the shaft 50 may be driven in one or the other direction by shifting the clutch 62 and that in its intermediate or neutral position the shaft 50 will not be driven at all from the shaft 55. The lever 63 may extend up through the floor of the house.

100 The shaft for raising or lowering the opposite ends of the elevating frame is designated 40. Each of the shafts 40 which operate the screws 34 is provided with a beveled gear wheel 64 which engages a beveled gear wheel 65 mounted upon a shaft 66. This shaft at its opposite end carries a beveled gear wheel 67, in turn meshing with a beveled gear wheel 68 mounted loosely upon a shaft 69. Operating on this shaft is a clutch 70 which is adapted to be shifted into or out of engagement with the beveled gear wheel 68 and this causes it to rotate with the shaft 69 or to run loose. Each clutch 70 is operated by means of a lever 71. Each shaft 69 also carries upon it a sprocket wheel 72, and the shaft 69 is operated from a countershaft 73 driven by the motor and having upon it the sprocket wheel 74 over which a sprocket chain passes to the sprocket wheel 72. This sprocket wheel 74 is loose 105 upon the shaft 73.

Also loose upon the shaft 73 is a gear wheel 75 which meshes with a gear wheel 76 mounted upon the shaft 69, and between the gear wheel 75 and the sprocket wheel 74 there is disposed the sliding detachable clutch member 77 operated by means of a lever 78. Obviously, when the clutch member 77 is engaged with the sprocket wheel 74, the shaft 69 will be operated in one direction, and when it is in engagement with the gear wheel 75 the shaft 69 will be operated in the opposite direction. The lever 78 also extends into the operator's room of the house 18; and by the use of this lever 78 and the two levers 71 it is possible to fully control the operation of the screws at opposite ends of the supporting frame and also operate the driving wheels to move the transporter in one direction or the other along the track.

It will be understood, of course, and particularly from Figure 1, that the lower portion of the operating room of house 18 is disposed below the level of the water in the canal B, and thus it will be obvious that all those shafts which project through the lowest floor of the house 18 must be packed so as to prevent any inlet of water, and that the lowest portion of the house must be entirely water-proof. Inasmuch as this house is very narrow, the mechanism illustrated in Figure 5 may be placed directly above the motor, which is on the lower floor of the house, and the mechanism illustrated in Figure 5 for operating the screws may be placed above the mechanism for operating the driving wheels. The operator's room may be placed above these two floors, the controlling levers sticking through the floor.

In the operation of this transporting apparatus, the boat to be transported is taken into the basin B and tied up to a post 79 on the land. The transporting mechanism is then rolled beneath the boat. When the transporter is at a suitable place where the boat may rest upon the cradle without placing strain upon the water wheel or screw and the rudder, then the boat's crew throw a rope over the posts 33 at either end, untying the boat from the post 75 and pulling the boat over against the posts 33 and fastening it there. At this point there may be two feet of water between the bottom of the boat and the cradle 43 more or less. Now the operator starts up the transporter and moves over this track, and inasmuch as the boat is fastened to it the boat is dragged with it. Now when the transporter moves onto the inclined track, the operator starts the mechanism illustrated in Figure 5 for raising the rear end of the elevating frame, and this is so timed that when the rear wheels of the transporter have reached the grade the rear end of the carrier or elevating frame is raised to a horizontal position.

Of course, at this time the safety lock 44 has been withdrawn at the rear end of the carrier, while at the front end of the carrier the lock is projected, securely holding the carrier to its trunnions. As the transporter goes up the grade it will, of course, raise the cable bed upward, bringing it closer and closer to the bottom of the boat until it touches at one point or another and starts to support the weight of the boat. As it recedes, it takes more and more of the weight of the boat until the boat is lifted entirely above the water. The transporter then moves on up the grade (see Figure 2), and as soon as the front wheel of the transporter touches the level stretch at the upper end of the grade, the rear end of the carrier or elevating frame is let down so that at about the same time the rear wheels of the transporter touch the level stretch at the top of the grade, the boatcarrier will rest on both of its trunnions again. The safety lock at this end is now projected. The carrier may be then moved down grade into a basin of water until the cradle 43 has released the vessel and moved down below the same, after which the vessel may be towed on out and the transporter may be then returned. If, on the other hand, the transporter is to carry a vessel not only up a grade as, for instance, a hill and then down again on the other side, then when it moves down the grade the safety lock on the front end of the transporter is withdrawn and as soon as the front wheels of the transporter touch the grade, the front end of the carrier is raised. As soon as the boat or vessel is floating free, it may be tied up to the bank and then the transporter withdrawn out of the way. The transporter is then ready for the next boat either way.

It will be seen that the boat or vessel is held in a horizontal position at all times without regard to whether there is a grade or not. The transporter needs only one man to handle it and power may be taken to the motor from an overhead trolley wire 80 by means of the trolley pole 81. Any other method of delivering electric current to the motor in the house 18 may be used or the motor may be driven by any other power than electricity. It will be seen that this mechanism permits vessels longer or shorter than the transporter to be lifted and transported and that these vessels are securely held in place without strain and supported along the entire length of the bottom. The cables 43 and the links 42 and the springs 41 are all yielding to permit the cables to conform to the bottom and distribute the strain all over the entire cradle. The vessel may be disposed within the transporter either with its bow or stern at

the forward or rear end of the transporter. Of course, the rear paddle wheels, propeller or rudder must project beyond the transporter, as illustrated, as these parts would 5 be damaged by the cables of the cradle.

I do not wish to be limited to the exact details shown, as it is obvious that these may be changed in many ways without departing from the spirit of the invention.

10 I claim:—

1. A boat transporting apparatus including a wheeled main frame having means whereby it may be propelled, a boat carrier, fulcrums disposed at opposite ends of the

15 frame and with which opposite ends of the carrier are adapted to engage, and means on the carrier for raising or lowering each end of the carrier independently of the other end.

20 2. A boat transporting apparatus including a wheeled main frame having means whereby it may be propelled, a boat carrier disposed above the main frame, fulcrums disposed at opposite ends of the frame

25 and with which opposite ends of the carrier are adapted to engage, elevating means mounted on the main frame at the opposite ends thereof and operatively engaging the carrier, and means on the carrier for independently operating the elevating means at

30 either end of the carrier whereby to hold the boat at all times in a horizontal position while the main frame is inclined.

35 3. A boat transporting apparatus including a wheeled main frame having means whereby it may be propelled, a boat carrier mounted upon the main frame, fulcrums disposed at opposite ends of the frame

40 and with which opposite ends of the carrier are adapted to engage, elevating means mounted on the main frame at the opposite ends thereof and operatively engaging the opposite ends of the carrier, means on the carrier for independently operating said

45 elevating means, and means for locking either end of the carrier to the main frame against vertical movement but permitting oscillation of the carrier.

50 4. A boat transporting apparatus including a wheeled main frame having means whereby it may be propelled along horizontal or inclined tracks, the main frame being formed to provide two opposite parallel vertical portions, a boat carrier disposed

55 within the main frame, means at opposite ends of the main frame constituting fulcrums for the boat carrier and upon both of which means the boat carrier rests when in a horizontal position, and means on the

60 main frame operatively engaging the opposite ends of the carrier whereby either end of the carrier may be raised or lowered independently of the other.

65 5. A boat transporting apparatus including a wheeled main frame having means

whereby it may be propelled either along horizontal tracks or inclined tracks, bearings mounted at opposite ends of the main frame, a boat carrier disposed within the main frame and having laterally projecting 70 trunnions engageable in said bearings, each of said bearings being open at its upper end whereby the trunnion may be lifted from the bearing, means at opposite ends of the frame whereby the corresponding end of the 75 carrier may be raised or lowered, and power means for independently operating said raising or lowering means.

6. A boat transporting apparatus including a boat carrier having upwardly extending 80 side members, a cradle adapted to receive the hull of the boat comprising transversely extending cables, and contractile springs connecting said cables to the lateral members of the carrier. 85

7. An apparatus for transporting boats from a basin at a lower altitude to a basin at a higher altitude and vice versa including rails disposed horizontally in said basin and at an inclination from the lower basin to 90 the higher basin, one of said rails being cogged, a transporter including a main frame having wheels and adapted to run upon said rails, certain of the wheels being cogged to engage the cogged wheel, power operated 95 means for driving said wheels, a boat carrier disposed within and carried by the wheeled main frame but free to move vertically with relation to the latter and having a cradle to engage the bottom of the boat, means at 100 opposite ends of the frame adapted to form a fulcrum for the opposite ends of the carrier means for locking either end of the carrier to the corresponding fulcrum, and means at each end of the main frame whereby that end of the carrier may be lifted to thereby tilt the carrier with relation to the main frame. 105

8. A boat transporting apparatus including a wheeled main frame having means 110 whereby it may be propelled either horizontally or up an incline, the wheeled frame being formed to provide vertically extending sides, a carrier having vertically extending sides disposed between the sides of 115 the main frame, a resiliently yieldable cradle mounted upon the upper end of the carrier and adapted to support the hull of a vessel, means at each end of the carrier and main frame whereby either end of the carrier may be fulcrumed upon the main frame, means for locking either end of the carrier to its fulcrum but said means permitting the other end of the carrier to be raised, and power operated means disposed at each end of the 120 main frame and engaging the corresponding end of the carrier whereby either end of the carrier may be raised or lowered. 125

9. A boat transporting apparatus including a wheeled main frame having means 130

whereby it may be propelled either horizontally or up an incline, the wheeled frame being formed to provide vertically extending sides, a carrier having vertically extending sides disposed between the sides of the main frame, a cradle mounted upon the upper end of the carrier and adapted to support the hull of a vessel, means at each end of the carrier and main frame whereby either end of the carrier may be fulcrumed upon the main frame, means for locking either end of the carrier to its fulcrum but said means permitting the other end of the carrier to be raised, jack screws mounted at each end of the main frame and operatively engaging each end of the carrier whereby either end of the carrier may be raised or lowered independently of the other end, and manually controlled power operated means for operating either set or jack screws.

10. A boat transporting apparatus including a wheeled main frame having means whereby it may be propelled either horizontally or up an inclined surface and having sides, a carrier disposed within said sides, the carrier supporting a cradle to engage the hull of a boat, open-ended bearing members disposed at opposite ends of the main frame, trunnions mounted upon the carrier at opposite ends of the carrier and engageable with said bearing members, means at opposite ends of the main frame and engaging the carrier whereby either end of the carrier may be raised from its bearings, means for locking either end of the carrier against movement off its bearings, a motor carried on the main frame and manually controlled means for applying the power of the motor to the elevating means at each end of the main frame whereby to cause either end of the carrier to be raised or lowered.

11. A boat transporting apparatus including a wheeled main frame having means whereby it may be propelled either horizontally or up an inclined surface and having sides, a carrier disposed within said sides, the carrier supporting a cradle to engage the hull of a boat, open-ended bearing members disposed at opposite ends of the main frame, trunnions mounted upon the carrier at opposite ends of the carrier and engageable with said bearing members, means at opposite ends of the main frame and engaging the carrier whereby either end of the carrier may be raised from its bearings, means for locking either end of the carrier against movement off its bearings, a motor carried on the main frame, manually controlled means for applying the power of the motor to the elevating means at each end of the main frame whereby to cause either end of the carrier to be raised or lowered, said means including a pair of parallel shafts, one of said shafts receiving power from the

motor and carrying upon it a loose sprocket wheel and a loose gear wheel, the other of said shafts having fixed upon it a sprocket wheel and a gear wheel, both of said sprocket wheels being connected by a sprocket chain, and a clutch mounted upon the first named shaft and shiftable into operative engagement either with the sprocket wheel of this shaft or the gear wheel thereof to thereby cause either the direct or reverse operation of the second named shaft.

12. A boat transporting apparatus including a wheeled main frame, means whereby it may be propelled, a boat carrier mounted within the main frame for vertical movement, means at opposite ends of the frame adapted to form opposite fulcrums for the carrier and permit either end to be raised relative to the frame, power operated means for raising or lowering each end of the carrier independently of the other end and including a power operated shaft having thereon a loose sprocket wheel and a loose gear wheel, a countershaft having thereon a fixed gear wheel engaging the loose gear wheel and the sprocket wheel, a chain connecting the two sprocket wheels, a pair of loose gear wheels mounted upon said last named shaft, a pair of clutches for connecting the last gear wheel to the shaft, a clutch mounted upon the first named shaft and engageable with either the sprocket wheel or the gear wheel, and means for transmitting the motion of each of the gear wheels on the second named shaft to the elevating mechanism.

13. A boat transporting mechanism including a wheeled main frame having means whereby it may be propelled either horizontally or up an incline and including side members, a house supported by said main frame at one side thereof, a boat carrier frame disposed within the main frame and to one side of said house, a yieldable cradle supported thereby and adapted to receive the hull of a boat, posts extending upward at one side of the boat carrier with which the boat may be engaged when on the cradle, bearing members mounted upon the main frame at opposite ends thereof but permitting free upward movement of each end of the boat carrier, means mounted upon the main frame at opposite ends thereof and operatively engaging the opposite ends of the boat carrier at a plurality of points whereby the ends of the boat carrier may be raised or lowered, trunnions mounted upon the boat carrier and projecting laterally therefrom and engageable with the bearings, means at opposite ends of the main frame for locking the corresponding end of the boat carrier to its fulcrum and unlocking the opposite end of the carrier from its fulcrum whereby it may be raised, and power operated means disposed within the

house for propelling the main frame or operating said raising and lowering means at either end of the main frame of the carrier.

14. A boat transporting apparatus including a wheel main frame having means whereby it may be propelled, a boat carrier disposed within the main frame, a plurality of jack screws at each end of the main frame, power operated means for rotating the jack screws, the carrier having at its ends longitudinally projecting members and a member at each end of the frame through which

the jack screws pass and having screw-threaded engagement therewith, said members extending beneath the projecting ends 15 of the carrier whereby when a set of jack screws is operated the corresponding end of the boat carrier will be raised, and means at opposite ends of the boat carrier and main frame for fulcrumming the boat carrier thereon. 20

In testimony whereof I hereunto affix my signature.

JOHANN J. R. HAALCK.
